UNITED STATES PATENT OFFICE.

DAVID F. PLATNER, OF SAN DIEGO, CALIFORNIA.

CONCENTRATOR.

Application filed July 25, 1922. Serial No. 577,275.

To all whom it may concern:

Be it known that I, DAVID F. PLATNER, a citizen of the United States, residing at San Diego, county of San Diego, and State of California, have invented new and useful Improvements in Concentrators, of which the following is a specification.

This invention relates to machines for separating metalliferous values from crushed ore, gravel and the like, and particularly to that type of machine in which the material is subjected to vibratory movement to obtain concentration.

The object of the present invention is to generally improve and simplify devices of the character described; to provide a concentrator over which the crushed ore, screened gravel, or the like, is caused to travel and there subjected to a vibrating or concentrating action; to provide riffles of a novel form in which the concentrates are caught or trapped; to provide means for preventing packing of the material while subjected to the concentrating action; to provide means for increasing the rate of flow or travel of the material undergoing concentration by angular adjustment of the concentrator, and to provide a structure whereby cleaning up or removal of the concentrates is facilitated. Further objects will hereinafter appear.

One form which my invention may assume is exemplified in the following description and illustrated in the accompanying drawings, in which—

Fig. 1 is a front elevation disclosing the preferred form of the device.

Fig. 2 is a side elevation of the same.

Fig. 3 is a longitudinal section through the gravity box.

Fig. 4 is a perspective view of the screen.

Fig. 5 is a central sectional view of Fig. 2.

Fig. 6 is a top plan view of Fig. 3 with the screen removed to show the interior construction of the box.

Referring more particularly to the drawings, A indicates a main frame embodying a pair of standards or jarring posts 11. These posts are rigidly supported in an upright position by base timbers 12, braces 14 and a top cross beam 15. Disposed between the posts 11 is a pair of movable uprights 16 and 16^a, the lower ends of which are supported in recesses 19^a formed in the base timbers 12. Such mounting permits movement of the upper ends of the standards

with relation to the jarring posts. As shown the uprights 16 are connected together at their upper ends by a cross-bar 17, which cooperates with a pair of cross-bars 18 and 19 in supporting a gravity separator or concentrating table 20. The cross-bars 18 and 19 are supported by cleats 21 in a horizontal position adjacent the top of vertical members 22. These latter members are rigidly secured at their lower ends to the base members 12.

As shown in the drawings, the cross-bar 18 is supported at a slightly greater height than the cross bar 19, while the cross-bar 17 assumes an intermediate position. Therefore, it is obvious that the concentrating unit will be supported on an incline. The cleats 21 are removably secured to the vertical members 22 so that the height of the cross-bars 18 and 19 may be adjusted. This, of course, also adjusts the angle of incline of the concentrator.

As shown in Fig. 2, the concentrator 20 is mounted between a pair of short uprights 23 which are rigidly secured to the central cross-bar 17 and are provided with slots 23^a for the reception of trunnions 23^b secured on the concentrator 20. The uprights serve to maintain the concentrator in position on said cross-bar when reciprocating or vibratory movement is imparted thereto.

As stated, a vibratory or reciprocating movement is imparted to the concentrating unit during the operation of the machine. This is accomplished through the medium of a driving sprocket 24 which is connected by a chain 25 to a driven sprocket 26. The latter is secured on a shaft 27 which is supported in bearings 28, the shaft 27 extending parallel to the top cross-beam 15. Mounted on the opposite end of the shaft 27 is a crank 29, the latter being connected by a connecting rod 30 to one end of a horizontal link 31. The other end of this link is connected to the upper end of an approximately centrally pivoted lever 32. This lever is pivotally mounted at the end of a rigid bracket 33. The lower end of the lever is connected by a connecting link 34 to the standard 16^a. It is seen that the connecting link mentioned passes through an opening 35 formed in the jarring post adjacent the standard 16^a. It should be obvious that rotating movement imparted to the driving sprocket 24, either by manual effort or mechanical means, will drive the shaft 27

and consequently the crank 29. Movement of the crank will impart vertical reciprocating movement to the connecting rod 30, which reciprocal movement will be translated into horizontal movement and transmitted to the connecting link 34 by the link 31 and the lever 32. As the link 34 is connected to the standard 16^a, rocking movement will be imparted to both the standards 16 and reciprocating movement imparted to the cross-bar 17 and consequently to the concentrator 20. The length of the stroke of the link 34 is such that the standards 16^a will contact at the end of each stroke with the jarring posts 11. The impact thus provided aids in the separating operation in the concentrator. The standards 16 and 16^a are guided for the movement mentioned by guides 16^b as shown.

Referring to Figs. 3 and 4, where the construction of the concentrator is more clearly illustrated, it is seen that it is provided with a plurality of transversely arranged riffles 38, which are constructed and arranged as shown. These riffles are preferably formed of sheet metal bent to form a rectangular trough with a flat bottom and straight sides 39 and 40. The upper end of the side 39 is bent outwardly, as at 41, and upwardly as at 42. To prevent the material being treated from packing between the riffles, a plurality of longitudinally extending wires or rods 43 are provided. These wires are passed through the riffles and are secured thereto in any suitable manner. It is seen that the wires are arranged in three rows which are spaced equidistance apart across the concentrator.

When treating placer gravel, it has been found necessary to provide the concentrator with a screening member 47. This member consists of an open rectangular frame 48 having a screen 49 at the top and a screen 50 of smaller mesh at the bottom. Each side of the screen frame is provided with pins 51 which are centrally located and adapted to fit in slots 23^a formed in the short uprights 23. The frame may be removably secured to the top of the concentrator in any suitable manner. It should be stated that when treating crushed ore, it is not necessary to employ the screen.

In operation, the device is constructed and assembled as shown in the drawings. The material to be treated is fed to the upper end of the screen through a hopper or other suitable means. Power may be applied to drive the sprocket 24, which, as described, will transmit reciprocating movement to the concentrator through the medium of the several mechanical elements mentioned. As the concentrator is tilted at a desired angle, the jarring action will cause the material to travel longitudinally of the concentrator and the heavier mineral prod-

ucts to settle to the bottom of the concentrator, while the lighter material or gangue passes over the riffles and discharges and packing of the material, while subjected to concentration, is prevented by the use of the wire rods 43 as these serve the function of agitators and thereby maintain the material in the state of agitation, which is of considerable importance as it permits separation and settling of the concentrates, and as previously stated prevents packing of both concentrates and pulp. In actual operation it may be stated that it is immaterial whether the material to be concentrated is handled dry or wet as the action in either instance will be similar, that is longitudinal flow or travel of the material is not dependent upon a flowing stream of water, but is caused by the longitudinal incline of the concentrator and the lateral vibratory movement transmitted thereto.

By referring to Fig. 3, it will be noted that the concentrating table is lined with metal as indicated at 60. This metal lining is in reality nothing more or less than a removable metal box which carries the riffle members and the rods 43. The metal box is trough-shaped and one or more of said boxes may be placed within the concentrator proper, the number depending entirely upon the length of the concentrator and the material handled. When cleaning up, it is only necessary to remove the metal boxes and these may then be placed over a pan or tub and the concentrates removed by applying water, for instance with a hose or otherwise. The concentrates thus removed may then be panned down or otherwise treated and the metal boxes replaced in the concentrator for further use.

From the foregoing it will be seen that the device here disclosed, while simple in construction and operation, provides a very efficient separator of large capacity which will be continuous in operation.

While the device here shown is more or less specifically illustrated, I wish it understood that various changes in form and proportion may be resorted to within the scope of the appended claims, similarly that the materials and finish of the several parts employed may be such as the experience and judgment of the manufacturer may dictate or various uses may demand.

Having thus described my invention, what I claim and desire to secure by Letters Patent is—

1. In a concentrator, a box, a lining therefor comprising side and end walls, a plurality of longitudinally extending rods carried by the lining, and transversely disposed riffles therein supported on the rods, the said aligning riffles and rods being removable as a unit from the box.

2. A concentrator comprising a frame

having a pair of base members, said members having a recess formed therein, a pair of standards, the lower ends of which are loosely disposed in said recesses, a cross-bar connecting said standards, a concentrating box centrally supported by said cross-bar, adjustable supports for each end of said box secured to said frame, and means connected to one of said standards for imparting movement to said standards to vibrate said concentrating box.

3. In a concentrator, a box, a series of riffles arranged transversely in the box and a plurality of longitudinally extending vertically spaced rods extending through said riffles.

4. In a concentrator, a box, a series of step-shaped riffles extending crosswise of the box, and a plurality of vertically spaced rods mounted in the box and extending through said riffles.

5. In a concentrator, a box, a series of step-shaped riffles disposed crosswise of the box, one of the sides of the riffles being extended outwardly and then upwardly to form upper L-shaped parts, and a plurality of rods extending at right angles to said riffles and passing through the same.

6. In a concentrator, a box, a series of V-shaped riffles arranged transversely in said box, one of the sides of said riffles being extended outwardly and then upwardly

to form upper L-shaped parts, and a plurality of rows of rods extending longitudinally of the box and through the riffles. 35

7. A concentrator comprising a frame embodying a pair of jarring posts and a pair of base members, the latter having sockets formed therein, a pair of standards mounted for rocking movement with their lower ends in said sockets, a cross-bar connecting said standards, a concentrator box mounted centrally on said cross-bar, a front and rear cross-bar having vertical supports secured to said base-members, the last named cross-bars being horizontally disposed and vertically adjustable on their supports, whereby the concentrator may be tilted to any desired angle, and mechanical means adapted to impart rocking movement to said standards to reciprocate the box, said standards being so located that they will contact with the jarring posts during such rocking movement to jar said box. 45

8. In a concentrator, a box, a series of step-shaped riffles extending transversely thereof, and a plurality of series of vertically spaced and aligned rods passing through the said riffles. 55

9. In a concentrator, a box, a series of step-shaped riffles extending transversely thereof, and agitating means carried by the riffles and extending at right angles thereto. 60

DAVID F. PLATNER.
